UNITED STATES PATENT OFFICE

WILLIAM H. BANAGAN, OF QUECHEE, VERMONT

WEFT END REMOVER FOR AUTOMATIC LOOMS

Application filed November 7, 1930. Serial No. 494,136.

The present invention relates generally to automatic looms and more particularly to means for preventing end portions of the filling extending from and ejected bobbin from being drawn into the shed on the first pick of the shuttle after a transfer has been made.

An important object of the invention is to provide, in a manner as hereinafter set forth, a device of the aforementioned character embodying a rotary brush which is associated with the lay of the loom in a manner to engage with the shuttle when said shuttle leaves its box on the first pick after a transfer has been made for removing the trailing end portion of the filling from the ejected bobbin from the eye and side of the shuttle.

Another important object of the invention is to provide a mechanism of the character described embodying novel means for driving the rotary brush from the picker ball shaft of the loom, the brush being mounted for swinging movement with the lay of the loom.

Another important object of the invention is to provide an apparatus of the character set forth embodying novel supporting means for the rotary brush whereby said brush may be adjusted toward or away from the shuttle box should it be so desired.

Other objects of the invention are to provide, in a manner as hereinafter set forth, a weft end remover for automatic looms which will be simple in construction, strong, durable, efficient and reliable in operation and which may be manufactured and installed on conventional looms without materially altering said looms structurally at low cost.

All of the foregoing and still further objects and advantages of the invention may become apparent from a study of the following specification, taken in connection with the accompanying drawings wherein like characters of reference designate corresponding parts throughout the several views, and wherein:

Figure 1 is a view principally in front elevation and partly in vertical section of an apparatus in accordance with this invention mounted in operative position on a loom.

Figure 2 is a vertical cross sectional view taken substantially on the line 2—2 of Figure 1 looking in the direction indicated by the arrows.

Figure 3 is a vertical cross sectional view taken substantially on the line 3—3 of Figure 1 looking in the direction indicated by the arrows.

Figure 4 is a fragmentary view in top plan looking downwardly from the line 4—4 in Figure 1.

Figure 5 is a detail view in perspective showing the adjustable brace or strut through the medium of which the rotatable brush may be adjusted.

Referring to the drawings in detail, it will be seen that the reference numeral 1 designates a lay having a shuttle box 2 at the replenishing side of the loom, said lay being provided with an elongated slot or opening 3 for the passage of a bobbin or the like 4 which is ejected from the shuttle 5 when said shuttle is in the box 2 by the transerrer 6.

A substantially U-shaped bracket 7 is mounted for swinging adjustment on the lay 1 through the medium of suitable anchoring pins or the like 8 which pivotally connect the upper ends of the arms of the bracket 7 to opposite sides of the lay 1. A horizontal shaft 9 is journalled in the arms of the bracket 7 and has fixed on one end portion a grooved pulley 10. A circular brush 11 is fixed on an intermediate portion of the shaft 9 between the arms of the bracket 7 and said brush is operable in one end portion of the elongated opening or slot 3 in the lay 1. The periphery of the brush 11 is usually substantially flush with the upper surface of the lay 1.

A brace or strut 12 is provided with an angular end portion 13 for connection with the lower portion of the bracket 7 and said brace or strut 12 is further provided with an angular slotted portion 14 adapted to be adjustably secured to the lower side of the lay 1 through the medium of a suitable bolt or the like 15. The bolt or the like 15, of course, extends through the slot 16 and is anchored in the lay 1.

Through the medium of the slot 16, the

bracket 7 may be swung in a vertical plane to adjust the brush 11 relative to the lay 1, as will be apparent.

A hanger 17 depends from the lower side of an intermediate portion of the lay 1 and has fixed on a lower portion thereof an angular bracket 18. A shaft 19 extends between the free ends of the hanger 17 and the bracket 18 and has mounted thereon a three step pulley 20. A substantially U-shaped bracket 21 is anchored on a lower or other support and has extending between the upper end portions of its arms a rod 22 upon which is mounted for swinging movement a substantially U-shaped member 23 having the free end portions of its arms apertured for the passage of the rod 22. A shaft 24 is mounted between the arms of the member 23 and journaled on the shaft 24 at spaced points are the grooved pulleys 25.

A grooved pulley 26 is fixed on the rotary shaft 27 of the automatic loom. An endless belt 27 is trained around the pulley 26 and has its flight trained under the pulleys 25 on the swingable member 23, said belt 27 then being trained over one of the elements of the pulley 20 as may be apparent, the swingable member 23 thus constitutes a gravity actuated belt tightener which maintains the proper tension on the belt 27 at all times and permits swinging movement of the pulley 20 and the hanger 17 with the lay 1 of the loom. The pulley 20 is operatively connected with the pulley 10 which drives the rotary brush 11 by an endless belt 28.

In operation, the brush 11 is driven from the shaft 27 of the loom through the medium of the endless belts 27 and 28 and the various pulleys with which the belts are operatively connected. When a transfer has been made and the ejected bottom or the like 4 drops into the usual can provided for the purpose, the rotary brush 11 will engage the end 29 of the filling when the shuttle 5 passes said brush on the first pick in a manner to remove the end 29 from the side and eye of the shuttle and thus prevent the end from being carried into the shed.

As before explained, the brush 11 may be adjusted relative to the lay 1 and the shuttle 5 through the medium of the swingable supporting bracket 7 and the adjustable brace or strut 12.

It is believed that the many advantages of a weft end remover for automatic looms, in accordance with this invention will be readily understood, and although the preferred embodiment of the invention is as illustrated and described, it is to be understood that changes in the details of construction may be had which will fall within the scope of the invention as claimed.

What is claimed is:

1. In a filling replenishing loom, the com-

bination of the lay having a shuttle box and provided with an opening for the passage of a bobbin when it is ejected from the shuttle, a rotary brush mounted on the lay having its axis at right angles to the longitudinal axis of the lay, said brush being operable in the opening in the lay to catch and hold the filling between an ejected bobbin and the shuttle box and prevent the filling end from being carried into the shed by the shuttle.

2. In a filling replenishing loom, the combination of the lay having a shuttle box and provided with an opening for the passage of a bobbin when it is ejected from the shuttle, a rotary brush mounted on the lay having its axis at right angles to the longitudinal axis of the lay, said brush being operable in the opening in the lay to catch and hold the filling between an ejected bobbin and the shuttle box and prevent the filling end from being carried into the shed by the shuttle, and means operatively connecting the brush to the operating mechanism of the loom for rotation thereby in a direction opposite to the direction of travel of the shuttle on the first pick after a transfer has been made.

3. In a filling replenishing loom, the combination of the lay having a shuttle box and provided with an opening for the passage of a bobbin when it is ejected from the shuttle, a rotary brush mounted on the lay and operable in the opening in the lay to catch and hold the filling between an ejected bobbin and the shuttle box and prevent filling from being carried into the shed by the shuttle and means for adjustably supporting the rotary brush for adjustment relative to the lay.

4. In a filling replenishing loom, the combination of the lay having a shuttle box and provided with an opening for the passage of a bobbin when it is ejected from the shuttle, a rotary brush mounted on the lay and operable in the opening in the lay to catch and hold the filling between an ejected bobbin and a shuttle box and prevent filling from being carried into the shed by the shuttle and means for adjustably supporting the rotary brush for adjustment relative to the lay, said means comprising a substantially U-shaped bracket having its end portions connected for swinging movement to opposite sides of the lay, said bracket depending from the lay, a brush supporting shaft mounted transversely in the bracket, and a brace having one end connected to the bracket and its other end adjustably secured to the lay for retaining the bracket against swinging movement in adjusted position.

5. In a filling replenishing loom, the combination of the lay having a shuttle box and provided with an opening for the passage of a bobbin when it is ejected from the shuttle, a rotary brush mounted on the lay, said brush rotating on an axis at right angles to the longitudinal axis of the lay, said brush being

operable in the opening in the lay to catch and hold the filling between an ejected bobbin and the shuttle box and prevent the filling end from being carried into the shed by the shuttle, means for supporting the rotary brush for adjustment relative to the lathe, said means comprising a substantially U-shaped bracket having its end portions pivotally connected to opposite sides of the lay, 5 said bracket depending from the lay, a brush supporting shaft journalled transversely in an intermediate portion of the bracket, a brace adjustably connecting the lower end portion of the bracket with the loom in a manner to retain the bracket against swinging movement in adjusted position, and 10 means operatively connecting the brush to the driving mechanism of the loom for rotating said brush in a direction opposite to the direction of movement of the shuttle when said shuttle is leaving the shuttle box to make the first pick after a replenishing operation has been completed.

6. In a filling replenishing loom, the combination of the lay having a shuttle box and provided with an opening for the passage of a bobbin when it is ejected from the shuttle, a rotary brush mounted on the lay and operable in the opening in the lay to catch and hold the filling between the ejected bobbin and the shuttle box and prevent the filling end from being carried into the shed by the shuttle, endless drive belts operatively connecting the rotary brush to the driving mechanism of the loom for actuation thereby, and a gravity actuated belt tightener operatively engaged with one of the driving belts.

7. In a filling replenishing loom, the combination of the lay having a shuttle box and provided with an opening for the passage of a bobbin when it is ejected from the shuttle, a bracket depending from the lay, a shaft journalled on the bracket, a rotary brush fixed on the shaft and operable in the opening in the lay to catch and hold the filling machine and ejected bobbin and shuttle box and prevents the filling end being carried into the shed by the shuttle, a pulley fixed on the shaft, a hanger depending from the lay, a multi-pulley mounted for rotation on the hanger, a pulley fixed on the picker ball shaft of the loom, a belt operatively connecting the second named pulley to the third named pulley for actuation thereby, a belt operatively connecting the first named pulley to the second named pulley for actuation thereby, and a gravity actuated tightener operatively engaged with the first named belt for maintaining said first named belt taut and for compensating for the swinging movement of the second named pulley with the lay.

8. In a filling replenishing loom, the combination of the lay having a shuttle box and provided with an opening for the passage of a bobbin when it is ejected from the shuttle,
